UNITED STATES PATENT OFFICE.

CHARLES R. HARRIS, OF WILLIAMSPORT, PENNSYLVANIA.

DESIGN FOR A BICYCLE-FRAME.

SPECIFICATION forming part of Design No. 26,589, dated February 2, 1897.

Application filed September 16, 1896. Serial No. 606,057: Term of patent 14 years.

To all whom it may concern:

Be it known that I, CHARLES R. HARRIS, a citizen of the United States, residing at Williamsport, in the county of Lycoming and State of Pennsylvania, have invented and produced a new and original Design for Bicycle-Frames, of which the following is a specification, reference being had to the accompanying drawing, forming a part thereof.

10 The accompanying drawing illustrates my design.

The leading feature of my design consists in a bicycle-frame having a continuous, unbroken, curved outline.

15 A represents the steering-head of a bicycle, and B the frame. Starting at the point a, the frame curves gradually downwardly, as at a', to a point somewhat in rear of the crank-hanger b, and then upwardly to the point c, so 20 as to mark approximately a semicircle. From the point c the frame curves downwardly,

merging in an approximately vertical portion d. At the lower end of the portion d the frame is curved rather abruptly, as at e, and then the frame extends upwardly in the form of an 25 easy compound curve, as at f, the upper end of part f being attached to the steering-head. The parts a' and f are connected together in advance of the part e of the frame by brazing, the brazed portion being preferably cov- 30 ered by a clip g.

The rear portion of the frame is bifurcated for the reception of the rear wheel, the axle of which is mounted in brackets secured to the frame.

35

What I claim is—

The design for a bicycle-frame herein shown and described.

C. R. HARRIS.
